ACOUSTIC ALARM DEVICE

Albert Hagger, Basel, Switzerland, assignor to Svenska Aktiebolaget Gasaccumulator, Lidingo, Sweden, a corporation of Sweden

Application October 3, 1956, Serial No. 613,644

Claims priority, application Germany October 13, 1955

3 Claims. (Cl. 116—70)

The invention refers to an acoustic alarm device for indicating when the gas pressure in a compressed-gas container sinks below a predetermined level. The sound-producing member is actuated by the gas leaving the container. A valve is closed by the gas pressure within the container and is opened by a controllable spring via a plunger when the gas pressure in the container sinks below a predetermined level. When the valve is open, a certain amount of gas flows to the sound-producing member.

Known alarm devices of this kind have certain disadvantages. The amount of gas flowing to the device and with it also the sound volume is dependent on the pressure in the container, which causes a relatively rapid decrease in the sound volume. Also, the alarm can only be made audible within a small pressure range, since the amount of gas for a sound-producing member may be varied only within narrow limits. On the contrary, however, it is desired that the alarm be audible with increasing volume until the container is emptied.

Known alarm devices have the further disadvantage that the valve does not automatically close when the container pressure is again raised. They must therefore be provided additionally with arrangements that permit the valves to be closed manually as well. This, however, makes the value of the device as an alarm arrangement questionable.

The invention has for its object to avoid these disadvantages and consists in the construction of the valve-opening plunger in the form of a piston slideable in the spring chamber and sealing the same in a gastight manner from the valve chamber, a passage being provided between the upper and the lower face of the piston for causing substantial throttling of the gas flowing to the sound-producing member. It is advantageous to construct this passage as a boring passing through the piston. In principle, however, it is also possible to provide a throttling passage in the wall of the housing or outside the same connecting the upper and lower piston face.

The drawing shows by way of example an embodiment of the alarm device in longitudinal section. It is shown threadedly connected with the compressed-gas container 1. The type of connection is however immaterial and may also be indirect, via a conduit. A valve 2 is held closed by the gas pressure in the container and additionally by a relatively weak pressure spring 3. The pressure spring 4 serves to open the valve via the plunger 5. The spring tension is regulated with the screw 6 so as to make the alarm device respond at the desired pressure, i.e. open the valve. The plunger 5 has the form of a piston and has a tight fit against the wall of the spring chamber. The sealing is preferably obtained by means of an elastic disk 7, such as a rubber disk pressing against the cylinder wall on the one hand and against the piston shank on the other. The piston is provided with a narrow boring 8.

2

In substantial contact with the lower face of the piston disk 11 is the face of the elastic disk facing the spring chamber, whereas the upper face thereof forms a seat for the pressure spring 4. The piston extends into the form of a pin serving as an interior guide for the pressure spring.

The spring chamber is connected through a boring 10 to the sound-producing member, which may comprise, for example, a pipe. The boring 10 is larger than the boring 8, so that when gas flows through with the valve 2 open a back pressure is exerted on the piston and counteracting the spring 4. The boring 8 is made barely large enough to ensure sufficient gas flow for actuating the alarm device. Through a correct choice of the relative dimensions of the borings 8 and 10, it is possible to control in the desired manner the time variation of the back pressure and the sound volume. Owing to the back pressure, the valve 2 opens only slowly and the issuing gas quantity increases with progressive emptying of the container. The back pressure also causes the retraction of the plunger 5 as soon as the container pressure is a little higher than the pressure at which the signal is to respond. The spring 3 serves to seat the valve, which is pressed against the seat by the container pressure.

What I claim is:

1. An acoustic alarm device for indicating decrease in pressure in a gas container below a predetermined value, comprising a chamber having a cylindrical wall, a piston slidably mounted in said chamber and in air-tight engagement with said wall, said piston dividing said chamber into a first portion and a second portion, said first portion communicating with said container, a valve disposed in said first portion, a valve closure member connected with said piston and cooperating with said valve, a first spring mounted in said first portion and urging said closure member to close said valve, a second spring mounted in said second portion in engagement with said piston and urging said closure member to open said valve, sound-producing means communicating with said second portion, and a first narrow duct communicating at one end with said valve and terminating at the other end in said second portion, said sound-producing means being responsive to gas flow through said chamber, and said first duct being adapted to admit only enough gas to cause response in said sound-producing means, whereby at said predetermined value said second spring opens said valve and gas flow through said first duct relative to flow to said sound-producing means regulates the rate at which said valve continues to open.

2. An acoustic alarm device according to claim 1 wherein said first duct is a narrow bore passing thru said piston and terminating at the face thereof adjacent said second portion.

3. An acoustic alarm device according to claim 1 further comprising a second narrow duct thru which said means communicates with said second portion, said second duct having a larger diameter than said first duct, whereby said means produces a sound of increasing volume until said container is emptied.
